(57) **CLAIM**

I claim the ornamental design for armless eyewear, as shown and described.

DESCRIPTION

FIG. 1 is a front isometric perspective view of a first embodiment of armless eyewear, showing my new design.

FIG. 2 is a rear isometric perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom view thereof.

FIG. 9 is a front isometric perspective view of a second embodiment of armless eyewear, showing my new design.

FIG. 10 is a rear isometric perspective view thereof.

FIG. 11 is a front elevation view thereof.

FIG. 12 is a rear elevation view thereof.

FIG. 13 is a right side elevation view thereof.

FIG. 14 is a left side elevation view thereof.

FIG. 15 is a top plan view thereof; and,

FIG. 16 is a bottom view thereof.

The broken lines depict portions of the article and form no part of the claimed design.

1 Claim, 16 Drawing Sheets
